FIG. 1 is a perspective view of a filter medium for an aquarium showing my new design;
FIG. 2 is a front elevational view thereof, the right side elevational view being a mirror image;
FIG. 3 is a rear elevational view thereof, the left side elevational view being identical;
FIG. 4 is a top plan view thereof, the bottom view being a mirror image;
FIG. 5 is a cross-sectional view thereof, taken on line 5—5 of FIG. 4;
FIG. 6 is a cross-sectional view thereof, taken on line 6—6 of FIG. 4; and,
FIG. 7 is a perspective view thereof, on a reduced scale, the broken line drawing of an aquarium is for illustrative purposes only and forms no part of the claimed design.
